UNITED STATES PATENT OFFICE

DONNELLY BROWN, OF KASSON, MINNESOTA

THERMOLUNCHBOX

Application filed December 2, 1930. Serial No. 499,545.

This invention relates to an improved thermolunchbox designed for individual use and especially constructed for conveniently holding and carrying diversified species of edibles, the same being suitable for camping and outing and also for carrying a daily lunch. Briefly stated, the novelty is predicated upon a box having its interior constructed to provide separate thermocompartments for reception of containers, and having its central portion constructed to accommodate accessories such as knives, forks, spoons, plates and the like.

The idea is distinguishable from prior art devices in that by providing separate compartments, it is possible to maintain certain of the edibles cold and other edibles hot, thus developing a unique hot and cold lunchbox.

The particular structural details and their relative arrangements and mechanical associations will become more readily apparent from the following description and drawings.

In the drawings:

Figure 1 is a front elevational view of a lunch box constructed in accordance with the present invention.

Figure 2 is a top plan view thereof.

Figure 3 is a transverse vertical section.

Figure 4 is a longitudinal vertical section on the line 4—4 of Figure 3.

The improved box is characterized by two primary parts, namely, a body or casing portion 5 of general rectangular configuration open on its front side, and a single hingedly mounted closure or door 6 for said open front. The door is hingedly attached by appropriate hinges 7 to the bottom wall 8 of the main box.

The upper edge portion is provided with suitable fastening devices or latches generally designated by the numerals 9 and these are engageable with the top walls 10 of the box. The door 6 embodies spaced parallel inter-connected plates 11 and 12 forming a container for the intervening insulation or packing 13, to provide the desired thermal properties for said door.

The door is of an area to swing tightly against the adjacent edge portions of the

mouth or opening of the main box to afford an efficient closure.

The numerals 14 and 15 in Figure 4 designate transverse longitudinally spaced partitions defining a central article compartment 16 containing knives, forks, spoons and the like, and also defining in conjunction with the end walls 17, a pair of individual end compartments, each end compartment including a rectangular shell or container 18 surrounded by packing 19. These insulated end compartments are designed for reception of a plurality of separate and individual holders or receptacles 20 and 21. I prefer to use two small receptacles 20 and a large receptacle 21 and to stack said receptacles within the container 18 as indicated in dotted lines in Figure 4.

On the bottom of the box are lugs or rests 22 constituting feet for conveniently supporting the box, and for allowing the front door to swing down to a horizontal position to serve as a tray or temporary shelf for accommodating the articles and edibles.

The numeral 23 designates suitable hand-grips or handles appropriately attached to the central part of the top of the box. Obviously, when the door is swung down, the end and the central compartments are exposed and convenient access is permitted thereto for reception of the various table articles and receptacles containing the edibles. One group of receptacles may be assembled for containing cold food and the other for containing hot or warm foods as the case may be.

Thus, I provide a simple, economical, and efficient portable lunch box which is expressly designed for carrying food either for daily usage by workmen, for example, or for the family on automobile trips and the like.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

A device of the class described comprising a casing having its front open, a pair of vertically arranged partitions in said casing dividing the same into a central chamber and two end chambers, a shell in each end chamber having its front open, packing material located between the walls of each shell and the walls of each end chamber and a door of the same area as the external area of the casing, having its lower edge hingedly connected to the bottom of the casing, said door being formed of a hollow member having packing means therein.

15 In testimony whereof I affix my signature.

DONNELLY BROWN.
